BOW TRIGGER MECHANISM

Clyde H. Konold, Magna, Utah

Application April 1, 1946, Serial No. 658,715

8 Claims. (Cl. 124—35)

1

This invention relates to a bow trigger mechanism for use in the sport of archery.

Among the principal objects of the invention are to provide:

(a) A mechanism in which an archer may securely and conveniently lock an arrow and then stress the bow string, finally causing the arrow to be discharged without danger of injury to the archer's fingers.

(b) A mechanism that is simple, durable and 10 not liable to get out of order.

(c) A mechanism in which the working parts are largely concealed though easily accessible when necessary.

(d) An embodiment that is neat and streamlined in appearance.

In the drawing, which illustrates one embodiment of the invention,

Fig. 1 represents a plan;

Fig. 2, a side elevation;

Fig. 3, an end elevation looking in the direction of the arrow 3, parts in the background being omitted;

Fig. 4, a transverse section taken on the line 4—4 in Fig. 1, parts in the background being 25 omitted;

Fig. 5, a plan, partially in horizontal section taken on the line 5—5 in Fig. 2;

Fig. 6, a plan, partially in horizontal section taken on the line 6—6 in Fig. 2, reflected from a 30 mirror plane;

Fig. 7, a transverse section taken on the line 7—7 in Fig. 5; and,

Fig. 8, a side elevation showing the device in the hand of a user with an arrow in readiness to be discharged.

Referring to the drawing, the numerals 10 and 11 respectively indicate two lever members that are connected together scissor fashion, in this instance by a pivot bolt 12. Each of the lever members extends along substantially a straight line and has at one end a gripper jaw 13, and at the other end a locking jaw 14. Thus the two levers are in close adjacency relatively to each other, which makes possible the compact arrangement that facilitates the novel interlocking thereof, and at the same time provides for novel breaking of the interlock by means of a trigger handle presently to be described.

Between the two levers 10 and 11 in the plane of the scissor action is a compression primary spring 15 that exerts its tension to normally hold the grippers 13 in an open position such as is illustrated in Fig. 6. The open position of the grippers however, is possible only when the locking jaws 14 are in a substantially closed position as indicated for illustration in Fig. 6. The closing of the jaws 14 is controlled by the positioning of a pawl 16 that forms an integral head on a stem 17, the latter being manipulated by means

2

of a trigger or handle 18 threaded thereon. Adjacent the handle 18 is an adjusting nut 19 against which bears a secondary compression spring disposed in a sleeve extension 21 of a housing 22. In this instance the handle 18 acts as a lock nut bearing against the adjusting nut 19, but if desired, the handle can bear directly against the spring 20.

The housing 22 is advantageously provided with finger-holding elements such as rings 23, in which a user's fingers are inserted somewhat after the manner illustrated in Fig. 8.

The operation of the parts so far described, is as follows:

When the grippers 13, Fig. 6, are closed by squeezing them together counter to the tension of primary spring 15, the leverage causes the jaws 14 to open. This allows the pawl 16 to be snapped into the open jaws, so that these bite upon the upper and lower surfaces of the pawl and clamp the latter in place. In this position, the trigger mechanism, including pawl 16, stem 17 and handle 18, may be said to be "cocked" under control of secondary spring 20. Pushing the trigger 18 instantly releases the pawl, thus opening the grippers 13 and closing the jaws 14.

In operation, assuming that an arrow 24 has been suitably positioned in the open grippers 13 of Fig. 6 so that the slotted end 25 of the arrow is brought into engagement with the bow string 26, Fig. 1, and assuming further that the user (not shown) is tensioning the bowstring as indicated in Fig. 8, the arrow is in readiness to be conveniently sent on its course. This results as soon as the user's fingers 27 and 28 engaging the rings 23, Fig. 8, are drawn inwardly toward the fleshy part 29 of the hand 30, whereby the spring 20 is compressed and the pawl 16 is pushed back into the position where the tension of the spring 15 is exerted to close the jaws 14, that is to say, to cause them to be snapped back into the position of Fig. 6.

In order that the end portion of the arrow may be held securely and yet may slip easily through the grippers 13, the latter are each provided with one or more inwardly curved, flexing fingers 31 that are in longitudinal alignment with the respective lever arms and grippers. The rear portions of the spring fingers 31 are anchored in the respective jaws as indicated at 32, while the forward ends of the fingers are free to move along the inside surfaces of the respective jaws.

Other details of the mechanism of the invention, as shown in the present instance, will now be described. To facilitate the cooperative action of the interconnected lever members 10 and 11, the latter, in the region of the pivotal connection, are advantageously provided with the respective, oppositely extending lugs 33 and 34 that are mutually shrouded for security and that

oscillate on the bushing 35. The bushing has its ends flush with the outside of the respective lugs so as to be covered and held in place by the housing 22 as well as being journaled on the pin 12.

The spring 15 is held centered by means of studs 36 projecting inwardly from the respective arms 10 and 11, while the jaws 14, in the open position indicated in Fig. 5, are accommodated in the overlapping portion 38 of the housing 22. Furthermore, the jaws 14 are recessed at 37, advantageously in a reversed D-configuration which accommodates closely the similarly configurated pawl 16 when the latter is in the position of Fig. 6. Also, the jaws 14 are channeled at 39 to accommodate the pin 17 when the jaws mutually close thereover to reach the position indicated in Fig. 6.

For the purpose of insuring durability and minimizing the wearing effect of rubbing against a bowstring, the grippers 13 are each provided with wear-resisting inserts 40, these being made of suitable material, such as agate.

The recess 37 is located along the respective pairs or sets of forwardly facing, stepped abutment surfaces 41 and 42 spaced apart as shown in Figs. 5 and 6.

The abutment surfaces 41 oppose the spring urge upon pawl 16 when the locking jaws 14 are in mutual alignment rearwardly of the open grippers 13 as in Fig. 6. Similarly, the abutment surfaces 42 oppose the spring urge upon pawl 16 after the grippers have been moved together and the locking jaws spread apart, as in Fig. 5.

Thus, in Fig. 6 the pawl 16 is under the urge of secondary spring 20 ready to be snapped into interlocked engagement with abutments 42 as soon as locking jaws 14 have been sufficiently spread apart. Again, in Fig. 5 the pawl 16 is in readiness to break the interlock as soon as handle 18 is given a push. This causes primary spring 15 to move grippers 13 apart.

It is to be observed that the abutments 41 and 42, together with adjacent portions of the locking jaws, actually form respective notches in which the pawl is alternatively seated.

While details that are more or less specific are necessarily described herein by way of illustration, no limitations are thereby imposed other than those set forth in the following claims.

What is claimed is:

1. A bow trigger mechanism, comprising two lever elements in pivoted scissor-like alignment throughout the length thereof; cooperative gripper jaws at the forward end of said pivoted elements; cooperative locking jaws having abutment means at the rearward end of the pivoted elements; primary spring means operable to open the gripper jaws; pawl means positionable for engagement by said abutment means counter to the tension of said primary spring means; and a trigger movable longitudinally of said lever elements to release the pawl means from said engagement.

2. A bow trigger mechanism according to claim 1, wherein the abutment means consists of two mutually spaced apart sets of transversely stepped abutment surfaces facing forwardly; wherein the pawl means alternately engages one set of said transversely stepped abutment surfaces and then the other, or vice versa; and wherein is included spring means that exerts its tension to hold the pawl means in contact with either set, as the case may be, of the said forwardly facing, transversely stepped abutment surfaces.

3. A bow trigger mechanism according to claim 1, wherein said abutment means consists of transversely opposed, recessed portions that together, when the locking jaws are closed, constitute a D-configurated recess; and wherein said pawl means includes a D-shaped pawl disposed to be moved into said recess by means of said trigger.

4. A bow trigger mechanism according to claim 1, wherein the two pivoted elements have apertured, mutually extending, opposing lugs nested side by side in mutually shrouded relation so that the respective apertures thereof are in axial alignment; a bushing extending through said apertures and having the ends thereof flush with the outside of the respective lugs; a housing holding said bushing in place; and pin means extending through the housing to hold the assembly operatively together.

5. A bow trigger mechanism according to claim 1, wherein are included wear-resisting inserts extending transversely of the gripper jaws so as to form a seat for a bowstring that is passed between said jaws.

6. A bow trigger mechanism according to claim 1, wherein are included springs inside the gripper jaws, the springs being compressible to hold an arrow frictionally in said jaws when closed, said springs being anchored at one end thereof, the other end of the springs being free.

7. A bow trigger mechanism, comprising two pivotally mounted, mutually separable grippers; a yielding tensioned member, normally holding the grippers apart; a pair of locking jaws extending in close mutual alignment rearwardly of the grippers and having mutually opposing abutment portions spaced transversely of said alignment; pawl means movable longitudinally into engagement with the spread apart locking jaws; spring means tending to urge said pawl means against said abutment portions thereby interlocking said locking jaws for the purpose of holding said gripper jaws closely together; and means manually operative to move said pawl means counter to said spring urge.

8. A bow trigger mechanism comprising two pivotally mounted, separable grippers normally held separated under spring pressure; locking jaws extending rearwardly of the grippers closely adjacent each other and adapted to be spread apart by moving said grippers together; two pairs of abutments spaced apart within said locking jaws; pawl means operative to engage the abutments, engagement with one of the pairs being effective to interlock the spread-apart locking jaws when and if said gripper jaws are closed; spring means tending to urge the pawl means into the interlocking engagement; and means manually operative to push said pawl means counter to said spring urge; thereby breaking said interlock and causing the spring pressed grippers to become separated.
